G. C. TAPLIN

OPERATING TABLE ATTACHMENT

Filed Jan. 14, 1922

INVENTOR
GEORGE C. TAPLIN

by Knight, Brown & Quincy, May 29, 1923

ATTYS.

UNITED STATES PATENT OFFICE.

GEORGE C. TAPLIN, OF BROOKLINE, MASSACHUSETTS.

OPERATING-TABLE ATTACHMENT.

Application filed January 14, 1922. Serial No. 529,191.

To all whom it may concern:

Be it known that I, GEORGE C. TAPLIN, a citizen of the United States, residing at Brookline, in the county of Norfolk and State of Massachusetts, have invented new and useful Improvements in Operating-Table Attachments, of which the following is a specification.

This invention relates to operating tables used by osteopaths, and other practitioners, who exert pressure in various directions on the recumbent body of a patient, the body usually lying on a cushioned horizontal operating table.

Letters Patent of the United States granted to me December 6, 1921, No. 1,399,634, discloses an operating table having means for exerting pressure in various directions and in various locations on the patient's body, and enabling the operator to utilize foot power, as well as manual power, in exerting such pressure.

The present invention has for its object to provide improved means whereby the operator is enabled to more conveniently, effectively and advantageously apply pressure to the patient's body than heretofore.

The invention is embodied in the improvements which I will now proceed to describe and claim.

Of the accompanying drawings forming a part of this specification,—

Figure 1 shows in transverse section an operating table, and in side elevation, a pressure-applying attachment embodying the invention, as it appears when in operation.

Figure 2 is a perspective view of the anchoring pulley, and the means for securing the same to the table, shown in section by Figure 1.

Figure 3 is a fragmentary side view of a portion of the bar and strap shown by Figure 1, showing a different way of utilizing the strap.

Figure 4 is a section on line 4—4 of Figure 1.

Figure 5 is a fragmentary side view, showing portions of the bar, pad and strap shown by Figure 1, and a link connecting the strap with the bar.

Figure 6 is a fragmentary perspective view, showing the link and a portion of the strap.

The same characters indicate the same parts in all of the figures.

The operating table shown by Figure 1, may be of any suitable construction, and may include a flexible body support 12, formed by the top of a pneumatic mattress and a frame including a fixed bottom 13, supporting the mattress, curb members 14, confining the mattress against horizontal displacement, and cushioned members 15 secured to the curb members, all as shown in my above-mentioned patent.

My improved pressure-applying attachment includes an elongated bar 17, having pulleys 18 and 19 at its opposite end portions, and a pressure pad 20 between its ends. One end of a strap 21 is connected as by a screw 22 with the bar 17, at a point near the inner pulley 18. From the connected end the strap 21 extends partly around the inner pulley 18, and from thence to the outer pulley 19, from which it depends, as shown by Figure 1.

23 represents an anchoring pulley provided with securing means engageable with a fixture on the table frame. A portion of the strap between the connected end and the inner bar pulley 18, is engaged with the anchoring pulley 23 by being passed under the latter, so that the anchoring pulley is in a bight of the strap depending from the inner end portion of the bar 17. The securing means with which the anchoring pulley is provided, is preferably embodied in a base plate 24, having upstanding ears 25, in which the anchoring pulley is journaled, and a confining arm 26, secured to the base plate, and having a hook 27, formed to detachably engage a fixture 28 attached to the table frame, said fixture being preferably an angle iron extending lengthwise of the table, and the hook being slidable along the fixture. There may be two fixtures 28, one at each side of the table, as shown by Figure 1. The arrangement is such that when the pad 20 bears on a body 29, or on the operator's hand 30, applied to the body, as shown by Figure 1, and the confining arm 26 is engaged with the fixture 28, the strap bight engaged with the anchoring pulley is adapted to swing freely in the directions required to permit horizontal endwise movements of the bar 17.

Said bight is also adapted to be lengthened, as indicated by dotted lines in Figure 1, to permit various inclinations of the bar. The bar may, therefore, be held in position to locate the pad 20

over various portions of the body 29, as shown by full and dotted lines, and may be inclined to accommodate the pad to more or less inclined or sloping portions of the body.

5 The free end of the strap 21 may be provided with a stirrup 32, to receive downward pressure from the operator's foot. Said pressure is exerted equally on both ends of the bar 17, in consequence of the connection 10 of the strap at 22 with the bar, and of the relative arrangement of the connected end, the anchoring pulley 23 and the bar pulleys 18 and 19, and this is the case whether the bar be horizontal or inclined.

15 The bar is preferably a hollow sheet metal tube of rectangular cross section, as shown by Figure 4. The pulleys 18 and 19 are within, and the portion of the strap extending between the pulleys is encased and 20 guided by the guideway formed by the interior of the bar. The bar thus formed and constructed is adapted to be grasped at its outer end portion, and at other portions by the operator, so that an additional handle is 25 not required. The free end portion of the strap may be turned inwardly and confined 30 against the bar by the operator's hand, as shown by Figure 3, so that the strap may be confined against endwise movement when 35 the operator desires to apply pressure by his hand alone.

The pad 20 is preferably a collar surrounding the central portion of the bar 17, and is preferably composed of a strip of felt, 35 coiled around the bar, as shown by Figure 4, and protected by a cover 20^a. This construction and the rectangular cross section of the bar enables the pad to be inexpensively and durably constructed, and retained by friction 40 in its operative position on the bar.

The strap 21 may be connected with the bar 17 by a U-shaped link (Figures 5 and 6) including a straight neck 33, arm 32, and trunnions 34, engaged with orifices in the opposite sides of the bar 17. One end of the strap is secured to the neck 33. Said neck portion is maintained parallel with the top and bottom sides of the bar and is longer than the width of the strap, the latter being 45 preferably an inch or more wide. The pulley 23 has a corresponding length. The strap has a wide bearing on the neck and on the pulley, and has a tendency to maintain the trunnions 34 parallel with the neck and with 50 the axis of the pulley, and thus assist a turning movement of the bar 17 on its longitudinal axis, and a rotary movement of the pad on the object on which it bears. The pad is therefore prevented from creeping or 55 moving progressively on said object, and thus undesirably or automatically varying the location of the applied pressure, a result which may occur when the strap is directly connected by the screw 22 with the bottom 60 side of the bar 17.

It will be seen that the end portions of the bar 17 projecting from the pad 20, constitute the weight and power arms of a lever of the second class, the weight arm being the portion shown at the right of the pad, said 70 lever being provided with guiding means embodied in the pulleys 18 and 19. The pad, located at the junction of said weight and power arms, constitutes the lever weight point. The anchoring pulley 23, engaged as 75 shown with the frame, constitutes the fulcrum. The strap 21 constitutes an elongated flexible lever extension, which is connected at one end to the weight arm, and includes a bight portion engaged with the pulley 23, 80 a running portion guided by the said guiding means, and a free end portion at the outer end of the power arm. The flexible lever extension 21 enables the lever to be operated advantageously in various positions. 85 The weight point formed by the pad 20 bears on a yielding support, while the fulcrum is immovable by strain exerted on it by the lever. The power applied, therefore, depresses the weight point. 90

I claim:

1. An operating-table attachment comprising an elongated bar, having pulleys at its ends, and a pressure pad between its ends, a strap connected at one end with the inner end portion of the bar and extending from the connected end over said pulleys to the outer end of the bar, one end of the strap being free and depending from the outer end of the bar, and an anchoring pulley provided 100 with securing means engageable with a fixture on the table, and engaged with a portion of said strap between the attached end and the inner bar pulley, the arrangement being such that when the anchoring pulley 105 is secured to the table, and the pad bears on a patient's body, the anchoring pulley-engaging portion of the strap forms a variable bight, permitting free endwise movements and various inclinations of the bar and pad. 110

2. An operating-table attachment comprising an elongated hollow bar, having pulleys at its ends, and a pad between its ends, a strap bearing on said pulleys, the bar being 115 open from end to end to encase and guide a portion of the strap between the pulleys, so that a portion of the bar may be utilized as a handle, and means for connecting the strap with an operating table, one end of the strap being free at the outer end of the bar. 120

3. An operating-table attachment comprising an elongated hollow bar, having pulleys at its ends, and a pad between its ends, a strap bearing on said pulleys, the bar being 125 open from end to end to encase and guide a portion of the strap between the pulleys, so that a portion of the bar may be utilized as a handle, and means for connecting the strap with an operating table, one end of the strap 130

being free at the outer end of the bar, the said pad being formed as a collar surrounding a portion of the bar and strap.

4. An operating-table attachment substantially as specified by claim 1, the said anchoring pulley-securing means being embodied in a base plate having upstanding ears, in which the anchoring pulley is journaled, and a confining arm secured to the base plate and formed to detachably engage said fixture.

5. In combination, an operating table, comprising a rigid frame and a yielding body support, an elongated floating bar, constituting the weight and power arms of a lever of the second class, and provided with guiding means, a pad mounted on the bar at the junction of said arms, a fulcrum member, means unyieldingly connecting said member with the table frame, and an elongated flex-

ible lever extension connected at one end with the weight arm, and including a bight-forming portion engaging said fulcrum member, a running portion guided by said guiding means, and a free end portion at the outer end of the power arm, the said pad constituting a weight point, adapted to be located over said yielding support and to be depressed by downward pressure on the power arm.

6. An operating-table attachment substantially as specified by claim 1, the strap being connected with the bar by a U-shaped link having a straight neck on which the strap bears, and arms provided with trunnions engaged with the bar between the top and bottom sides thereof.

In testimony whereof I have affixed my signature.

GEORGE C. TAPLIN.
